(54) **GOLD, AMALGAM MILL FOR SPARATING
FROM ORE**

(76) Inventor: **Joseph Curtis**

Joseph Curtis

The Schedule referred to in these Letters Patent and making part of the same, containing a description in the words of the said Joseph Curtis, himself of his improvement in the amalgam mill for separating Gold from the Ore.

To all to whom these Presents shall come.

Be it known that I Joseph Curtis have invented certain new and useful improvements in an amalgam mill to take Gold from the Ore, and that the following is a full and exact description of the construction and operation of said machine as invented by me.

A pot or bed piece made of cast iron $\frac{1}{2}$ an inch thick, the pot part $\frac{1}{2}$ a 10 inches diameter and $1\frac{1}{2}$ deep to the aperture in the center of an $\frac{1}{2}$ inch diameter to drain off the quicksilver by a cock or thumb screw b from the edge of the pot. a is a plain or flange $\frac{1}{2}$ $\frac{1}{4}$ inches diameter then a descending flange d $\frac{1}{2}$ 2 inches deep. To this flange is riveted a cylinder of sheet iron c $\frac{1}{2}$ $1\frac{1}{2}$ of an inch thick and $1\frac{1}{2}$ inches deep at the top and outer side is riveted a wrought iron hoop 1 inch broad and $\frac{3}{8}$ of an inch thick from this cylinder a piece of discharge is spent f of sheet iron 3 inches square the upper part of which is within 2 inches of the top (this spent may be contracted by means of blocks of wood as the quantity of the ore may require).

A frame of timber say 3 inches square for the uprights and $2\frac{1}{2}$ inches by 6 inches for the cross pieces is required to support the tube g on which the pulley H is attached for a band, this frame of timber is secured to the mill by bolts and nuts passing through the descending flange a and the timber and also by two bolts

and fully passing through the wrought iron hoop C (at the upper end of the cylinder) and the timber; in the pit within 2 inches of the bottom a wrought iron bar C, say one inch broad and half inch thick is horizontally placed the ends resting on the casting in a bed chipped for that purpose, in the centre of the bar is a hole half an inch in diameter to receive and support the receiving tube g which is of cast iron $2\frac{1}{4}$ inch calibre and $\frac{3}{8}$ of an inch thick and about 30 inches long having its lower end capped by a wrought iron plate with a vertical pin m that runs in the $\frac{1}{2}$ inch hole in the iron bar.

Holes of about $\frac{1}{16}$ of an inch are made in the wrought cap and end of the tube below the lower iron-capping plate equalling or nearly the sectional area of the tube, to secure the bar C in its place a wrought iron hoop not riveted m is put inside the pit the same being about $\frac{1}{16}$ inch thick and 2 inches deep, on this rests the plate N of 10 inches diameter and $\frac{1}{8}$ of an inch thick having a round hole in the centre of 5 inches diameter this is secured to its place by another hoop similar to m (and in like manner as many plates as may be required) and the whole is secured by the upper plate P 11 inches in diameter which is raised in its place by small screws going into the pit.

To the cast iron tube l inch from the bottom (resting on a small projection in the casting) is a thin wrought iron hoop) shunk to the tube is a sheet iron plate, $\frac{1}{8}$ of an inch thick and 9 inches diameter than a sheet iron hoop or sleeve $\frac{3}{8}$ of an inch thick and 2 inches broad than another plate similar to P all of which and more if required are bedded on by clay or wedges.

S. is a floating scowler made of pine plank 2 inches thick and 22 inches diameter the bottom of which is covered with sheet copper to keep this true and perfectly level it is attached to a wood tube 3 1/2 inches thick and 14 inches long that fits the tube but not so tight as to prevent its rising and falling as the fluid may require in the upper end of this tube is inserted an iron box ll (a cast iron box does well) a groove is chipped $\frac{1}{4}$ of an inch square lengthwise of the box ll and a wrought iron feather or key about 4 inches long is fitted to this groove and secured to the cast iron tube. To the outer edge of this wooden scowler is attached a sheet iron cylinder $\frac{1}{8}$ of an inch thick and 12 inches deep to stiffen this cylinder a wrought iron hoop $\frac{1}{4}$ or $\frac{3}{8}$ of an inch thick and 1 inch broad is riveted at the upper edge inside this cylinder P.

The pulley ll for the band is permanently fitted with a cast iron box ll inside and projecting above the pulley say one inch which runs in the bushes X fitted in the cross beam. the cast iron box can be adjusted so as to keep the tube in its place (which when the quicksilver is in the pot is pressing upwards).

To the cast iron tube a pipe of iron, iron or copper Y with a tunnel top is inserted of sufficient length to be equal to the hydrostatics pipes required which for the machine he named must be 60 inches.

The quicksilver must fill the pot and say 1 inch deep on the plain, or flange of 24 inches. The scowler which floats must have a weight of sand or water inside to cause it to settle, say $\frac{1}{2}$ an inch into the quicksilver.

The ore must be reduced to an impalpable

powder either by dry or wet process, when prepared for this mill it must be wet and conducted in a running stream of water into the tunnel of the upper tube whence it will find its way by its gravity through the orifices in the lower end of the tube and through the quicksilver to the discharge spout f. in the direction of the arrow.

The intent of giving the centre part a circular motion is to insure a more thorough distribution of the ore and water among the mercury. The quantity of ore to the measure of water depends on the earthy state of the ore.

The revolutions of the mill may be supposed to average 16 a minute but all depends on the quality of the ore.

And I Joseph Curtis do hereby claim as my invention the application of hydrostatic pressure to the passing of ore through a stratum of quicksilver by means of the mechanical combination set forth in the above described mill or by any other combination that may be performed.

Joseph Curtis
